UNITED STATES PATENT OFFICE.

VALENTINE SCHUCK, OF NEW YORK, N. Y., ASSIGNOR TO THE SUTRO BROTHERS BRAID COMPANY, OF NEW YORK.

DESIGN FOR BRAID.

SPECIFICATION forming part of Design No. 18,588, dated September 4, 1888.

Application filed August 9, 1888. Serial No. 282,363. Term of patent 14 years.

To all whom it may concern:

Be it known that I, VALENTINE SCHUCK, of the city, county, and State of New York, have invented and produced a new and original Design for Braid for Trimming Ladies' Garments and for other Purposes; and I do hereby declare that the following is a full and exact description thereof, reference being had to the accompanying drawing, and to the letters of reference marked thereon, making a part of this specification, in which my new design is illustrated by a view in perspective, upon an enlarged scale, of a piece of braid with its end cut transversely to show its outline in cross-section.

The braid A presents in its general configuration the appearance of two cylindrical cords applied longitudinally to each other and to one edge of a flat-sided rectangular strip. In cross-section it presents an outline bounded by two parallel side lines, *a a*, which terminate at one end in a cross-line, *b*, at right angles therewith, and at the opposite end in segments *c c* of circles severally described about centers

which are respectively outside of said lateral lines *a a* and beyond the ends thereof, and whose peripheries intersect said lines, and also intersect each other to form a central cusp, *d*, beyond the ends of the lateral lines, as shown in the drawing.

What I claim is—

The design for a piece of braid herein shown and described, which consists in the form imparted thereto, whereby it is bounded in its cross-section by parallel lines terminating at one end in a transverse line to form a rectangle and at the other in curved lines describing two circles springing from each lateral straight line, and which intersect to form a central cusp beyond said lines.

In testimony whereof I have signed my name to this specification in the presence of two subscribing witnesses.

VALENTINE SCHUCK.
